CLAIM

The ornamental design for a compartmented dish or the like, substantially as shown.

DESCRIPTION

FIG. 1 is a top perspective view of a compartmented dish or the like showing my new design;

FIG. 2 is a front elevational view thereof;

FIG. 3 is a top plan view thereof;

FIG. 4 is a bottom plan view thereof;

FIG. 5 is a side elevational view thereof; and

FIG. 6 is a cross-sectional view thereof taken along line 6—6 of FIG. 3.
